GROVER W. GILLELAND, OF PARSONS, KANSAS

BURIAL VAULT

Application filed May 27, 1929. Serial No. 366,412.

This invention relates to burial vaults of that class known as surface vaults or individual mausoleums and functioning both as a casket container and as a marker or headstone. Vaults of the character indicated are now being widely employed as they afford not only better protection against vandalism but also against ravages by the elements, and preserve the body, if properly embalmed, against disintegration for an indefinite period.

It has been found that vaults of the character under consideration are more efficient in their preservative action, if the air in the casket chamber is kept dry, and in accomplishing this result resort has been had to the provision of a dead air chamber overlying the casket chamber. The object of this invention is to utilize the principle involved in the last mentioned construction and to make provision for circulation of air between the two chambers to remove the moist air from the casket chamber to the overlying chamber, and to furthermore provide a more effective seal between the body of the vault and the cover or top plate thereof.

To this end, the invention consists in certain novel and useful features of construction as hereinafter described and claimed; and in order that it may be fully understood, reference is to be had to the accompanying drawing, in which:

Figure 1 is a view partly in elevation and partly in central longitudinal section of a vault embodying the invention.

Figure 2 is a view partly in end elevation and partly in cross section.

Figure 3 is a perspective view, on a reduced scale, of the completed vault.

Referring to the drawing in detail, 1 indicates the body portion which preferably is of size to contain a plurality of sizes of caskets, and is provided at a suitable height with internal upwardly-facing shoulders 2 along the sides and ends, and at a suitable height above said shoulders, is provided with an internal substantially V-shaped annular groove 3, the bottom of which slopes downwardly and outwardly.

50 A sealing member 4 providing a chamber

5, and preferably of the same configuration but shorter and narrower than the body portion, is fitted centrally within the latter and is provided with marginal base flanges 6 to overlie and rest upon the shoulders 2, and said flanges are preferably formed in their upper sides with grooves 7. Form plates 8 of metal are anchored at their lower ends in the flanges 6 inward of the grooves 7, said plates being off-set inwardly at 9 to widen the space between them and the surrounding walls of the body portion. The plates project upward to approximately the plane of the upper edge of the body portion, and terminate in downwardly and inwardly 65 extending flanges 10 which abut the adjacent upper corners of the member 4, being spaced therefrom as indicated to provide a dead air space enclosing the top, sides and ends of member 4, and to insure more uniform expansion and contraction of member 4, the flanges 10 are preferably perforated at 10^a to establish communication between the upper and lower parts of the dead air chamber. 75

The cover or cap plate 11 corresponds in 75 contour and exterior dimensions to the body portion and overlies same and member 4 and is provided with a depending annular tongue 12 extending down into the spaces between the form plates and the walls of the body portion, the exterior sides of the tongue having grooves 13, the bottoms of the grooves extending downwardly and inwardly. 80

The members 1, 4 and 11, are of molded concrete made in suitable forms, and the annular space within the body portion and surrounding the form plates 9 is filled with a proper cementitious material as at 14, this material being deposited or poured before the top plate or cover is placed in position, and being of such consistency that it shall enter and fill the grooves 3 and 13, and serve as a means of locking the cap in place. The joint between the upper edges of the body portion, which preferably slopes downwardly and outwardly slightly, is also filled by a suitable cementitious material for the purpose of sealing said joint against the entrance of water, the joint being made more effective 90 by providing the upper edge of the body por- 95

tion and the lower edge of the overlying portion of the cap or cover, with grooves 15 and 16, which not only cooperate in excluding water but provide an interlocked relation through the instrumentality of the joint-filling material, against longitudinal or lateral shifting of the cap or cover with respect to the body portion. It will be noted that by the use of the grooves 3 and 13 and 10 the filling therein, that the joint between the filling material and the surrounding wall and surrounded flanges 12, will guard against the seepage of water downward within the body portion more effectively by reason of the fact 15 that if water should seep into said grooves, it would have to rise until it cleared the upper edges of the inclined bottoms of such grooves before it could pass further downward.

The cover is preferably hollowed out at 20 its under side at 17 to increase the capacity of the air space above member 4, and for aesthetic appeal and water drainage purposes the upper surface of the major portion of the cap or cover is arched or rounded as at 18. 25 At the head end, the cover or cap is provided with a pillow block 19 wherein is moulded a suitable metal or other inscription plate 20 to bear the name, age and other information relating to the deceased to be enclosed within 30 the mausoleum.

As heretofore adverted to it is very desirable to effect the removal of moisture exuding from the body enclosed within a casket placed within the lower or casket chamber, as tending, provided the body is properly embalmed, toward preserving it in a natural state for an indefinite period. To accomplish this, means are provided for effecting an air circulation within the casket chamber and the chamber of member 4. As shown a tube 21 is molded within the member 4 so as to communicate at its lower end with the upper part of the body portion chamber and at its upper end with the upper portion of the chamber of member 4. A perforated tube 22 extends longitudinally in the bottom of the chamber of member 4, and extends through the lower part of said member and terminates at its lower end near the bottom of the casket chamber, the depending portion being identified by number 23.

For the purpose of more effectively absorbing the moisture from the air which rises through tube 21, a suitable absorbent, such as calcium chloride, is provided in the chamber of member 4, and to guard against this clogging the perforations of pipe 22, the latter is enclosed within a screen 24.

As temperature changes occur air will circulate up through tube 21 and the air in chamber 5, as it cools will pass down through tube 22 and its extension 23 into the casket chamber, the rising air carrying off moisture 65 from the last-named chamber, which mois-

ture is absorbed by the calcium chloride or its equivalent, and eventually by capillary or other action passes upward through the member 24, the overlying air chamber and the cap or cover.

It has been demonstrated in practice by the opening of vaults of this general class after a long period of time, that the interiors were found perfectly dry, and that bodies exhumed after a period of several years were found in an apparently perfect state of preservation. It has also been found that the heaving of the ground due to atmospheric changes has left the mausoleum in perfect condition and that they do not crack under extremes of freezing temperatures, it being understood of course that the parts are reinforced with woven wire or metal rods to give them proper tensile strength, which reinforcements have not been shown, as conventional in concrete work and hence not involving invention.

From the above description, it will be apparent that I have produced a burial vault possessing the features of advantage set forth as desirable in the statement of the objects of the invention, and which is susceptible of modification in various particulars within the principle of construction involved and the spirit and scope of the appended claims.

I claim:

1. A burial vault comprising a hollow body portion having internal upwardly-facing shoulders, a hollow intermediate portion within and spaced from the walls of the body portion and provided with outwardly-projecting base flanges resting on said shoulders, upright form plates enclosing and spaced from the intermediate portion and anchored thereto, a cover resting on the base portion and spaced from the intermediate portion and provided with a continuous tongue depending into the body portion intermediate the walls thereof and said form plates, and a cementitious filling upon the flanges of the intermediate portion and between the form plates and the walls of the base portion and forming a bed receiving said tongues of the cover.

2. A burial vault comprising a hollow body portion having internal upwardly-facing shoulders, a hollow intermediate portion within and spaced from the walls of the body portion and provided with outwardly-projecting base flanges resting on said shoulders, upright form plates enclosing and spaced from the intermediate portion and anchored thereto, a cover resting on the base portion and spaced from the intermediate portion and provided with a continuous tongue depending into the body portion intermediate the walls thereof and said form plates, and a cementitious filling upon the flanges of the intermediate portion and between the form plates and the walls of the base portion and

5 forming a bed receiving said tongues of the cover; the opposing faces of the tongue and base portion walls having grooves which receive parts of said filling, the bottoms of said grooves sloping downwardly and inwardly and downwardly and outwardly respectively.

3. A burial vault comprising a hollow body portion having internal upwardly-facing shoulders, a hollow intermediate portion 10 within and spaced from the walls of the body portion and provided with outwardly-projecting base flanges resting on said shoulders, upright form plates enclosing and spaced from the intermediate portion and anchored thereto, a cover resting on the base portion and spaced from the intermediate portion and provided with a continuous tongue depending into the body portion intermediate the walls thereof and said form 15 plates, and a cementitious filling upon the flanges of the intermediate portion and between the form plates and the walls of the base portion and forming a bed receiving said tongues of the cover; the form plates 20 terminating in flanges sloping downwardly and inwardly to the upper corners of the walls of the intermediate portion.

4. A burial vault comprising a body portion having a casket chamber, a cover resting 25 upon and for sealing engagement with the body portion, and provided with a continuous tongue depending within and spaced from the upper part of the body portion an intermediate hollow portion within the body 30 portion and below and spaced from the cover and provided with base flanges, form plates anchored to the flanges of the intermediate portion and spaced from the ends and sides thereof, and provided with perforated top 35 flanges sloping downward and inward to the intermediate portion, and cementitious material filling the space between the walls of the body portion and the form plates.

5. In a burial vault having a casket chamber, an intermediate hollow portion closing 40 the casket chamber, and a cover above and spaced from the intermediate portion, an air tube communicating with the upper parts of the casket chamber and the chamber of the 45 intermediate portion, and a tube communicating with the lower parts of said chambers.

6. In a burial vault, a hollow base portion, a cover therefor, an intermediate portion 50 closing the chamber of the base portion below the cover, the intermediate portion having an air chamber, and tubes respectively connecting the upper portions and the lower portions of the chambers of the base portions and intermediate portion.

60 In testimony whereof I affix my signature.
GROVER W. GILLELAND.
